UNITED STATES PATENT OFFICE

117,275

DESIGN FOR A TOY

Harold Jenkins, Tuba City, Ariz.

Application April 26, 1939, Serial No. 84,556

Term of patent 14 years

To all whom it may concern:

Be it known that I, Harold Jenkins, a citizen of the United States of America, residing at Tuba City, in the county of Coconino and State of Arizona, have invented a new, original, and ornamental Design for a Toy, of which the following is a specification, reference being had to the accompanying drawing, forming a part thereof.

In the drawing:

Figure 1 is a side view of the toy, showing my new design,

Figure 2 is a front view, and

Figure 3 is a rear view.

I claim:

The ornamental design for a toy, as shown.

HAROLD JENKINS.
